UNITED STATES PATENT OFFICE.

JAMES A. WALSH, OF INDIANAPOLIS, INDIANA, ASSIGNOR TO THE INDIANA MANUFACTURING COMPANY, OF INDIANAPOLIS, INDIANA, A CORPORATION OF WEST VIRGINIA.

PNEUMATIC STRAW-STACKER.

No. 872,868.

Specification of Letters Patent.

Patented Dec. 3, 1907.

Application filed August 12, 1907. Serial No. 388,073.

To all whom it may concern:

Be it known that I, JAMES A. WALSH, a citizen of the United States, residing at Indianapolis, in the county of Marion and State 5 of Indiana, have invented certain new and useful Improvements in Pneumatic Straw-Stackers, of which the following is a specification.

My invention relates to improvements in 10 folding pipes especially adapted for use with pneumatic stackers of that class composed of sections designed to be folded, and consists in an arrangement whereby I am enabled to swing the foldable section in any 15 predetermined direction in relation to its adjoining section.

Folding stacker pipes as ordinarily employed are arranged to be swung vertically where it is desired to swing a section or sections thereof over on the separator, and horizontally when desired to reduce the length of the pipe as a whole under certain conditions, as when threshing in barns, storage houses or other inclosures, where 25 space is so limited as not to admit of the ordinary long stacker pipe on the separator being swung around into position; and by the means which I employ, permitting the section to be folded either vertically, horizontally, or intermediate those positions, such section can be folded in any desired direction, so that if space is too narrow to permit complete horizontal movement of the folded pipe the section may be swung vertically, and, if sufficient movement can not be obtained in either of these directions, the folding section may be brought to a point between the horizontal and vertical either on the upper or lower portion of the fixed 35 40 pipe section and the most available space in the inclosure thus utilized to obtain free movement of the folding pipe section.

The accompanying drawings illustrate my invention.

Figure 1 is a side elevation illustrating the application of my said invention; Fig. 2 a transverse section looking in the direction indicated by the arrows 2—2 in Fig. 1; Fig. 3 a side elevation on an enlarged scale with 45 the hinge in position for swinging the outer pipe section vertically; Fig. 4 a detail sectional view on a still further enlarged scale in the direction indicated by the arrows 4—4 in Fig. 2; Fig. 5 a plan of the revolving 50 hinge; and Fig. 6 a side elevation showing 55 fragmentary pipe sections folded one above the other, dotted lines indicating other positions to which the folding section may be swiveled and folded.

In the drawings the invention is shown as 60 applied to a two-section stacker pipe, the section 10 being revolvably mounted upon the separator, and the outer section 11 hinged 65 attached to said section 10. Suitable reinforcing bands, 12 and 13, the latter also constituting a hinge-band, are riveted or otherwise suitably secured to the meeting ends of the pipe sections respectively, the band 13 on the outer section 11 being provided with arms, 14, 15, one of said arms, as 15, terminating in a ratchet member. Surrounding band 12 on pipe section 10 is a rotary or swiveling ring, 16, which may be in two parts clamped thereabout by means of lugs, 17, and screws, 18, (Fig. 2), or otherwise movably secured thereon. This ring and band 12 may be fitted to each other in any desired manner, and, as an example, I have shown (Fig. 4) the ring provided with an internal groove fitting over a flange on said band. 70 Said ring 16 is also provided with arms, 19, 20, the latter being a ratchet member, which arms, when placed in alinement with arms 14, 15, and connected by pintle, 21, constitute a ratchet hinge, the movability whereof 75 is controlled by a suitable locking device, such as tail-nut, 22. Collar, 23, is preferably mounted upon the hinge pintle as indicated, which collar, together with tail-nut 22, serve to retain ratchet members 15 and 20, and 80 also prevents the pintle from longitudinal displacement. The meeting ends of the pipe sections when brought together are secured in position by any suitable locking means, that shown consisting of lugs, 24, 25, 85 on ring 16 and band 13, respectively, on the opposite side of the hinge, one of the lugs, as 24, being provided with a hinge bolt, 26, which engages the slotted lug 25, and is securely held therein by thumb-screw, 27, this 90 arrangement insuring that the pipe sections are held securely together by a substantially air-tight joint. It will be understood, of course, that where the material of which the pipe is composed is of sufficient thickness and 95 rigidity the bands 12 and 13 may be dispensed with, as it is obvious that the swiveling ring 16 may be directly mounted on the pipe and connected to a fixed hinge member 100 on the adjoining pipe, and a suitable lug or 105 110

catch provided opposite said fixed member to engage appropriate fastening means on the ring.

The pipe sections when locked, as shown in Fig. 3, are rigidly held together, and the outer section prevented from turning. As shown in this view, the hinge is positioned so that section 11 may be raised and folded back above section 10. When it is desired to fold the pipe sections, the pivotal bolt 26 is released by unscrewing the thumb-screw 27, when pipe section 11 may be readily folded back in line with section 10, and securely held in place by tightening the tail-nut or other locking means for drawing the ratchet members together, the frictional engagement between them preventing them from slipping or turning, and, together with the opposite arms, 14, 19, and pintle 21, forming a rigid structure for fixedly sustaining the folded section above, along the sides, or beneath the section to which it is connected. As will be readily understood, when it is desired to fold section 11 in any predetermined position it is only necessary to turn said section, which, being hinged to ring 16, simultaneously revolves said ring, so that if said section is to be folded horizontally along either side of section 10, or below, or above, or intermediate such positions, the hinge is moved about to the desired point, the pipe section folded back, and the lock-nut 22 tightened, causing the ratchet members to be clutched, and the section thus held securely in folded position.

I claim as my invention:

1. A folding stacker pipe composed of sections connected by a swiveling hinge, means for locking said sections in extended position, and means associated with said hinge for fixedly maintaining the swinging section in any position to which it has been swung relatively to its supporting section.

2. The combination, in a pneumatic stacker, of a sectional pipe, means for rotating and folding a section of said pipe to any predetermined position relatively to its adjoining section, and locking mechanism associated with said means for fixedly maintaining said section in such folded position.

3. The combination, in a pneumatic stacker, of a folding pipe, means for folding a section of said pipe to any predetermined position relatively to its adjoining section, and means associated with said folding means for fixedly maintaining said folded section in such position.

4. The combination, with a pneumatic stacker, of a sectional discharge pipe, a hinge connecting said sections, said hinge being fixedly secured to one of said sections and movably mounted upon the adjoining section, and means opposite the hinge joint for

fixedly engaging the meeting ends of said sections and disengaging the same. 65

5. The combination, in a pneumatic stacker, of a sectional discharge pipe comprising a fixed section and a folding section hingedly and rotatably mounted thereon, and means associated with said sections for 70 fixedly maintaining said folded section alongside said fixed section.

6. The combination, with a sectional pipe, of a swiveling hinge member, a hinge member pivotally connected thereto, and means 75 for locking said members and preventing pivotal movement thereof.

7. The combination, in a pneumatic stacker, of a discharge pipe comprising a fixed section, a hinged section rotatably 80 mounted thereon, means for locking said sections in extended position, and means for locking said hinged section when folded in relation to said fixed section.

8. The combination, with a sectional pipe, 85 of a hinge-band fixedly connected to one of said sections, a reinforcing band fixedly connected to the adjoining section, a swiveling ring mounted on said band, hinged members comprising ratchets connecting said hinge-band and said ring, and a lock-nut for fixedly securing said ratchet members in engagement. 90

9. The combination, with a sectional pipe, 95 of a hinge member connected to one of said sections, a ring movable mounted upon the adjoining section, a ratchet hinge connecting said band and said ring, means for locking said hinge when one section is swung to a predetermined position in relation to the 100 other, and means for locking said pipe sections when in extended position.

10. The combination, with a sectional pipe, of a band embodying hinge members one of which is of ratchet form, a ring embodying hinge members corresponding to those of said band, a pintle connecting said hinge members, a stop for limiting the movement of said pintle, and a lock-nut for maintaining said ratchet members in frictional 110 engagement. 105

11. The combination, with a sectional pipe, of a band provided with hinge members one of which is of ratchet form, a ring provided with hinge members corresponding to those of said band, a pintle connecting said hinge members, means for drawing said ratchet members into engagement, and means opposite said pintle for locking said band and said ring when brought together. 115 120

In testimony whereof I affix my signature in presence of two witnesses.
